UNITED STATES PATENT OFFICE.

MARCEL BAILLY, OF PARIS, FRANCE.

HOLDER OR CONTAINER FOR TABLETS OF SOAP.

Application filed September 10, 1921. Serial No. 499,721.

To all whom it may concern:

Be it known that I, MARCEL BAILLY, a citizen of the French Republic, residing at Paris, France, have invented certain new and useful Improvements in Holders or Containers for Tablets of Soap, of which the following is a specification.

This invention relates to holders for cakes of soap and refers more particularly, but not exclusively, to articles of the class in question adapted for use with cakes of soap provided with reinforcing members by means of which they can be suspended.

It has for its principal object to provide a device or article upon which a cake of soap can be conveniently suspended by means of the reinforcing member, each time the cake is used, the device or article being also adapted to hold the cake in a most favourable manner for its preservation, for purposes of transport.

According to the general principle of the invention the device is made in the form of a box with a cover, the box being provided on the interior with means for engaging the reinforcing member of the tablet or cake of soap, which member is exposed for this purpose. In addition one of the constructional parts of the box is provided with means for suspending the tablet outside the said part, when such part is rested upon a suitable support, which support may in some cases be constituted by the other part of the box which may in this case be fitted with means for attaching the two parts together.

The invention includes in addition to the before mentioned constructional details, which are preferably used together but may be employed separately, certain other details which will be described more fully hereafter.

In order that the said invention may be clearly understood, I will now proceed to describe the same with reference to the accompanying drawing, it being clearly understood that the description and drawings are given merely by way of example.

Fig. 1 is a front elevation of a container for a tablet of soap, in the form of a box and constructed according to the invention.

Fig. 2 is a section upon a plane parallel

to Fig. 1 and passing through the middle of the container.

Fig. 3 is an inner view of the cover of the container.

Fig. 4 is an outside elevation parallel to the elevation in Fig. 1 showing the body of the soap container with the cover resting thereon and supporting a cake of soap.

The invention is illustrated as utilized for supporting a tablet of soap *a* of the kind provided with a reinforcement *b*, for instance of metal wire and furnished at two opposite points with means of suspension *b*¹ constituted by the parts *b*¹ of the wire left exposed and adapted to be engaged upon hooks. The container or box is constructed substantially as follows:—

c is the body of the box constructed in any suitable manner and of any desired shape. *d* is the cover. Within this cover the tablet *a* can be suspended by means of the parts *b*¹ of the reinforcement *b* from hooks *e* suitably located so that the tablet when placed in position is held immovable with the plane of the reinforcing member substantially parallel to the bottom of the box. The arrangement is moreover such that, when thus placed in position, there is a certain amount of space left between the surface of the cake and the container.

I prefer that the means of attachment shall be constituted by means of springy hooks, so that by bringing the hooks nearer together they may be engaged in the parts *b*¹ for suspending the tablet, which, when thus placed in position and the hooks are released is firmly held in place. The hooks are moreover so located that they do not interfere with the placing of the cover in position, and they may be independent of one another, or, preferably they may be formed from a single piece *e*¹ attached at the middle to one of the surfaces of the box, preferably to the surface of the cover, as shown in the drawing, care being taken to shape the edges of the side walls, for instance with cut away portions *d*¹, so that it is easy, when holding the tablet of soap in the plane of the reinforcement with the fingers to engage the parts *b*¹ with the means of suspension, that is to say with the hooks.

With this construction, when the soap has been suspended in the box, and the box closed, the soap can be transported without touching the walls of the box, and there is no risk, consequently, even if it is wet that it will not be properly preserved. Holes may be provided in the walls of the box so as to permit of ventilation and to facilitate the drying of the soap.

10 Means may be provided for securing the cover in position. For instance I may provide a spring *f*, fixed at one end to one of the members of the said box and so arranged as to press at the other extremity against the other part of the box when closed.

I prefer so to arrange that the soap when removed from the supporting hooks can be suspended from one of the parts of the box, preferably from the cover *d*, from one of its suspension points *b*¹, in such a way that the tablet hangs in position and may be removed and replaced with facility when required for use or after use.

20 With this object in view, I prefer to make the box in the shape of a parallelepiped, and I pivotally connect to one of the sides of the cover opposite to the hooks *e*, a projecting arm *g*, of such length and so provided at its free end with a hook *g*¹ that when the arm has been turned perpendicular to the bottom of the cover and this latter is placed in position so that it rests upon the opposite side, the tablet can be suspended from one of the parts *b*¹ of the reinforcement from the said hook *g*¹ without coming into contact with the cover.

25 In this way, the tablet is ready for use as soon as the cover has been supported in the way just described upon any suitable flat surface.

30 With advantage I may use one of the flat surfaces of the body of the box for this purpose, preferably the bottom surface, as shown at Fig. 4, the body being then rested upon the edges of the opening upon a flat surface.

35 I may provide means for fixing the cover in the desired position. For this purpose I may connect to the surface one extremity of a springy tongue *h*, which may frictionally engage between itself and the surface of the box the edge of the cover at the bottom. The tongue or tongues are so arranged as to avoid water which might run from the hanging tablet falling upon the bottom of the box, the tablet being held so that it is not over the box—see Fig. 4.

40 In this way I obtain a device or article for containing a tablet of soap which is of great practical use.

45 As will be clearly understood, and as has already been mentioned, the invention is not limited in any way to those methods of carrying it out or to those constructional embodiments which have been more partic-

ularly described, but includes all modifications coming within a fair interpretation of my claims:—

50 In some cases, for instance, the suspension member *g* may be used both as the projecting arm and as the spring *f*—this latter spring being then omitted. In this instance the piece *g* is pivoted to the same wall of the cover as previously described, but on the interior, and it is so formed that it is slightly springy so as to cause the cover to be pressed into contact with the body of the box, when the box is closed. The soap in this case would hang on the inner side of the cover and the tongues *h* would be so arranged as previously mentioned, that the tablet would not cause moisture to drop onto the body of the box.

55 In some instances the hooks *e* would be provided with extensions *e*², so that the parts *b*¹ for suspending the tablet could be engaged at one operation with the resilient hooks upon the box and so that by pressing upon the tablet, the parts *b*¹ of the means of suspension would automatically engage over the hooks which would hold the tablet in position when the hooks spring outwards.

60 What I claim and desire by Letters Patent of the United States of America is:—

1. In a holder or container for a tablet 95 of soap of the kind provided with a reinforcement, parts of which are left exposed for the purpose of suspending the tablet, the combination of the body portion, a cover and means upon one of the portions adapted to 100 engage the tablet of soap.

2. In a holder or container of the type described, the combination of a body portion, a cover portion, means upon one of the portions for holding the tablet of soap on 105 the interior of the box when closed and means on one of the portions for suspending the tablet of soap when required for use, substantially as described.

3. In a holder or container of the type 110 described, the combination of a body portion, a cover portion, means for holding the tablet of soap from one of the portions when the box is closed, and means such as a spring for holding the cover upon the body of the 115 box when the same is closed.

4. In a holder or container of the type described, the combination of a body portion, a cover portion, means for holding the tablet of soap within the box attached to 120 one of the portions and means attached to one of the said portions from which the tablet of soap can be suspended when in use, substantially as described.

5. In a holder or container of the type 125 described, the combination of a body portion, a cover portion, means upon one of the portions for holding the soap within the box, means upon one of the portions from which the tablet can be suspended and means for 130

attaching the two portions together when the tablet is suspended substantially as described.

6. In a holder or container of the type described, the combination of a body portion, a cover portion, spring members upon the interior of the cover portion, adapted to engage the reinforcement of a tablet of soap, and to hold the soap in position on the interior without touching the box, a pivoted 15 arm upon the cover adapted to hold the sus-

pended tablet and spring means for inter-engaging the box and the cover, substantially as and for the purposes set forth.

In testimony whereof I have hereunto set 15 my hand in presence of two subscribing witnesses.

MARCEL BAILLY.
